UNITED STATES PATENT OFFICE

165,857

SAUCER OR SIMILAR ARTICLE

Carlton L. Nelson, East Aurora, N. Y., assignor to John Wanamaker Philadelphia, Philadelphia,
Pa., a corporation of Pennsylvania

Application January 12, 1951, Serial No. 13,776

Term of patent 7 years

(Cl. D44—9)

To all whom it may concern:

Be it known that I, Carlton L. Nelson, a citizen of the United States, residing in East Aurora, Erie County, State of New York, have invented a new, original, and ornamental Design for a Saucer or Similar Article, of which the following is a specification, reference being had to the accompanying drawing, forming a part thereof, in which:

I claim:

The ornamental design for a saucer or similar article, as shown.

CARLTON L. NELSON.
